UNITED STATES PATENT OFFICE.

JOSIPHINE ROVIRA, OF NEW YORK, N. Y.

BRASSIÈRE.

1,144,001.

Specification of Letters Patent. Patented June 22, 1915.

Application filed April 4, 1912. Serial No. 688,351.

To all whom it may concern:

Be it known that I, JOSIPHINE ROVIRA, a citizen of the United States, and a resident of the city of New York, borough of Manhattan, in the county and State of New York, have invented a new and Improved Brassière, of which the following is a full, clear, and exact description.

The object of the present invention is to combine and distribute the fatty tissues of a female figure so as to impart a more pleasing bust configuration.

A further object of the invention is so to distribute and apply stiffening means to a brassière as to cause a forward distribution of the fatty tissues under the arms and cause the same to continue apparently into a bust configuration, either artificial or natural.

In carrying out the objects of the invention an effect is desired similar to that to be obtained by a woman grasping her two sides up under the arms by the palms of her hands and with separated fingers forcing the fatty flesh forward where it is held in pleasing configuration by the forwardly flaring fingers. This effect is preferably accomplished in the embodiment of the invention by a series of stiffeners suitably secured to the brassière at the locality under the arms and extending forward and decidedly flared in a forward direction to terminate over the locality of each bust.

The above will be understood more clearly by reference to the following specification, which should be read in connection with the illustrative embodiment shown in the accompanying drawings forming a part of this specification, in which similar characters designate corresponding parts, and in

which—
Figure 1 is a pictorial view of a person wearing a brassière constructed and arranged in conformity with the present invention; Fig. 2 is a back view of the brassière shown as worn on the person; Fig. 3 is a detail view showing a fragment of half section of a brassière constructed in accordance with the present invention, part of the structure being cut away to show the interior structural elements thereof; and Fig. 4 is a vertical section of a brassière having secured thereon a breast-form constructed and arranged in accordance with the present invention; Fig. 5 is a detail view in vertical section, on an enlarged scale, taken through the pocket provided to hold dress shields.

The body of the brassière may be constructed from any suitable textile fabric shaped and formed for encircling the wearer. The number of gores or sections making up the same is immaterial, although in the illustrative embodiment it is shown constructed in two sections, the sections being joined at the back by elastic bands 9, said bands being permanently incorporated in the structure. Each side section of the brassière is provided adjacent the edges joined by the bands 9, with a stiffener 10. The stiffeners 10 may be constructed from any suitable material, such as corset-steel, whalebone, celluloid or other suitable material well known in the art. The stiffeners 10, 10 operate in the present instance to prevent the crumpling or wrinkling of the unsupported edge of the garment. The front of the section of the garment is provided with fasteners 11 of any suitable form, such, for instance, as a button and buttonhole, or glove-fastening snap. To the fastening edge of one of the sections of the brassière is secured a flexible loop 12, having at the lower end thereof an eyelet 13, suitable for engaging one of the studs of the ordinary corset. The loop 12 may be constructed from elastic material, if such be found desirable. The sections of the brassière are joined by pierced edging strips 14, through the piercings whereof are threaded drawstrings 15. The strings 15, when drawn, hold the brassière in position upon the person and upon the corset.

It will be understood that the brassière herein shown and described is designed to fit the body of the person above the corset, and to overlap the upper edge of the corset.

The brassière is provided with shoulder-straps 16. The straps 16 may be constructed of flexible or elastic material, as desired. Adjacent the arm-hole of the brassière is formed a pocket 17. The pocket 17 is provided to hold one side or wing of a dress-shield 18. It will be understood that the dress-shield 18 may, when desired, be incorporated in the structure of the brassière, by sewing to the inner side of the pocket thus formed, and to an extension of the material from which the brassière is constructed, a suitable, and preferably a washable, rubber cloth, such as is commonly used in the construction of dress-shields. When this form of construction is adopted, the pocket 17 may be utilized for the reception of some

form of scent, such as what is known as sachet powder. Further, the pocket thus formed may be used to more thoroughly ventilate the portion of the garment where 5 the shield is placed, by opening the pocket, to more thoroughly aerate the structure when the same is not being worn. Each section of the brassière is provided between the back panel and the front panel thereof, with 10 breast-supporting sections extending across the side of the wearer below the arm and above the corset, said sections embodying a series of stiffeners 19. The stiffeners 19 as seen in the drawings are fanned or flared 15 toward the forward end of the structure, or adjacent the front panel of the garment. This arrangement provides structures which yield to the strain of the brassière, gradually toward the front thereof, to conform to 20 the shape of the breasts of the wearer. As seen in the drawings, one of the breast-forms 20 is worn, the spread portions of the grouped stiffeners 19 resting above the said form. Where the form is not used, the 25 spread ends of the stiffeners 19 rest against the side of the breast of the wearer, operating to support any fatty tissues at this part of the body, to maintain the same in the desired advanced position. While I have 30 shown in the drawings a series of only three stiffeners 19, it will be understood that these stiffeners may be multiplied, or augmented to cover a wider area of the structure than herein shown. It will be noted that, by the 35 superposed arrangement of the stiffeners 19, the desired flexibility of the garment, to permit the same to accommodate the bending of the body, is here provided for. The breast-form 20 shown in the accompanying drawings 40 consists of a rounded shape constructed from crinoline or ruffled material, such as

that indicated by the numeral 21 in Fig. 4 of drawings. The crinoline is sewed to a thin pad 23, which gives body to the structure. The pad 23 is securely attached to a 45 strap 22, at the ends whereof is mounted a fastener 24, whereby the breast-form is attached to the brassière and subsequently held thereby in position. By means of this arrangement, the breast-form may be substituted, repaired, or the use thereof discontinued, by unfastening the strap 22 from the garment. Thus whether or not the breast formation is natural or artificial the fanned or flaring stiffeners 19 effect a blending of the fatty tissues of the sides of the wearer into the bust outline under the flare of the stiffeners. It should likewise be noted that this function is in no way impaired by the shield pockets 17 which are illustrated in 50 relation to the side stiffeners. 55

Having thus described my invention, I claim as new and desire to secure by Letters Patent:—

A brassière for forming and confining busts comprising a fabric-body for encircling the wearer and having a series of elongated stiffeners on each side, each stiffener extending from the rear portion back of an arm forward to the position of a bust, the individual stiffeners of each series being flared apart toward the front whereby the fatty tissue may be confined under the arms and be brought forward to blend into a bust outline under the flare of the stiffeners. 65 70 75

In testimony whereof I have signed my name to this specification in the presence of two subscribing witnesses.

JOSIPHINE ROVIRA.
